UNITED STATES PATENT OFFICE.

CHARLES ASHWELL, OF KEARSNEY, NATAL, SOUTH AFRICA.

SAFETY-RAZOR.

1,180,963.

Specification of Letters Patent. Patented Apr. 25, 1916.

Application filed January 20, 1916. Serial No. 73,204.

To all whom it may concern:

Be it known that I, CHARLES ASHWELL, a subject of the King of Great Britain, residing at Fawsley Park, Kearsney, in the Province of Natal, Union of South Africa, have invented certain new and useful Improvements in Safety-Razors, of which the following is a specification.

This invention is for a new or improved form of safety razor in which a blade usually two edged, of sheet steel, is fixed in a handle having guards on both sides of the plate so that it acts like a plane, and planes the hair away, the handle being tubular in whole or in part, and part of it formed as a screw or tightening device so as to tighten the two guard plates against each other on opposite sides of the razor blade, the upper and lower plates being slightly convex and concave so as to bring a strain on the blade when screwed up.

The razor consists of four parts, fitted together, and is best described by aid of the accompanying drawings, in which,

25 Figure 1 is an end view of the entire razor, Fig. 2 a section at right angles thereto through the center line, Fig. 3 a plan view of the lower guard, and Fig. 4 a plan view of the razor blade.

30 In these 1 is a thin steel blade sharpened on both sides 2, 2.

3 is a hiatus cut out of this blade to fit the projection 4 of the stem 5 as hereafter described. This projection 4 can be of any 35 desirable form, its object being to hold the two cover plates hereafter described.

6 is a cover plate having projections 4 as already described and machined so as to be somewhat concave on the underneath side.

40 It has a stem 5, projecting from the center downward at an angle of 25 degrees, and screwed at the end at 8. 7 is a second cover plate on the opposite sides of the plate. It also is slightly curved to the same curvature 45 as the lower side of plate 6. These give a strain on the blade, and thus hold the latter rigid. This cover plate is shaped so as to allow all the projections 4, and stem 5 to pass into or through it. It has brazed to it 50 a tubular projection 9 and it is suitably milled as shown in Fig. 1 so as to become a firm handle.

10 is a tubular nut screwed so as to fit the screw 8. This nut is also milled, and 55 with the part 9 forms the handle.

The plate 7 has preferably a series of slots at both edges which will give way slightly when the whole is pressed up, and will act also as a guard for the plate. The best angle at which the stems 5 and 9 should project from the head has been found by experiment to be 65 degrees, but this may be slightly altered without much injuring the utility of the invention.

In assembling the parts together, the part 6 is preferably placed with its stem 5 upright. The blade is now fitted on the parts 4 entering the orifice 3 in the blade. The cover plate 7 and the stem 9 previously brazed together (they could be made in one 70 piece with difficulty) are next applied. The part 10 is then screwed on to the screw 8 until it comes tight up against the stem 5. The whole is now tightly fixed together. To use the razor, the operator simply grasps 75 the stem 8, 9, and shaves with either of the two sides 2, the parts 6 and 7 acting as guards to prevent the blade 2 cutting the skin.

I claim as my invention—

As an improved article of manufacture, a safety razor comprising a lower cover plate of oblong form having a depending central hollow handle, downwardly inclined guard teeth at its two longer edges, said 80 plate formed in its upper face with a central depression and set, in the direction of its length, diagonally to said hollow handle, an oblong duplex blade having a central opening, an upper oblong cover plate 85 parallel with the lower plate and having a central projection extending through the blade aperture into the said central depression, and a central stem extending down through the hollow handle and provided with a 90 threaded lower end, and a handle extension having a threaded socket engaging said threaded lower end, the adjacent faces of the cover plates being curved to place the blade 95 under strain, whereby the razor may be used 100 with a sidewise shearing movement in lieu of a downward pull.

In witness whereof, I have hereunto signed my name this 7th day of Dec. 1915, in the presence of two subscribing witnesses. 105

CHARLES ASHWELL.
